UNITED STATES PATENT OFFICE.

NICOLAS EMILIE METHLIN, OF PARIS, FRANCE, ASSIGNOR TO SCHNEIDER & CIE., OF PARIS, FRANCE, A LIMITED JOINT-STOCK COMPANY.

GUN BARREL.

Application filed October 25, 1926, Serial No. 144,067, and in France January 14, 1926.

The present invention relates to a gun barrel adapted to be taken down or dismounted, comprising a jacket forming a breech sleeve at its back part and a firing tube encased 5 at its back part in the said jacket.

According to the invention the thickness of the firing tube, its external diameter and the nature or state of the metal of which it is composed are chosen in such a way that 10 when the gun barrel is mounted a clearance is left between the back part of the tube and the interior of the jacket which is taken up each time a shot is fired in order that the jacket will assist the gun barrel in withstanding the transverse stresses set up, the 15 said clearance re-appearing automatically, however, after the projectile has left the gun, thus enabling a worn firing tube to be easily removed and replaced by a new tube.

20 In order that the jacket will take part in withstanding the transverse stresses set up in the gun barrel during firing, that is to say, in order that the assembling clearance will disappear momentarily while re-appearing 25 automatically subsequently when the de-forming force due to the pressure of the gases has ceased to act, a metal having a higher elastic limit than the metal of the jacket may be chosen for the firing tube.

30 The jacket and the firing tube may also be both made of the same steel and the steel of the firing tube have a higher elastic limit imparted to it by a suitable treatment.

35 The removable firing tube may also be made of a metal having, in desired cases, an elastic limit lower than that of the metal forming the jacket. In this case it will be necessary to subject the tube, in a preliminary operation, before the machining of the 40 tube, to a treatment which raises the elastic limit of the outer layers of the tube, making it higher than the elastic limit of the inner layers of the jacket. This effect may be obtained by subjecting the firing tube, before machining, to a self hooping operation.

45 Several embodiments of the present invention are disclosed in the accompanying drawings wherein like reference characters refer to like parts throughout the several views.

50 It will be understood, however, that the drawings are for purposes of illustration only and are not designed as a definition of the

limits of the invention, reference being had to the appended claims for this purpose.

In the drawings, Figs. 1 and 1^a constitute 55 a longitudinal sectional view of one embodiment of the invention.

Figs. 2, 2^a and 3 are similar views illustrating other embodiments.

In the example shown in longitudinal sec- 60 tional elevation in Figure 1 the firing tube A inserted from the front in the jacket B with a clearance D is screwthreaded at a for its assembly with the jacket which is pro- 65 vided with a corresponding female thread b. This thread is of the opposite hand to the rifling of the tube.

The rear end of the tube is turned down at a¹ to form a shoulder a² by means of which the tube presses upon an abutment b¹ 70 formed upon the jacket.

75 As the screwed joint and the rifling have opposite handed threads no unscrewing of the tube can take place during firing; moreover, the tube is always made to abut against the shoulder in the jacket by the screwing action, which the reaction due to the rotation of the projectile in the tube tends to produce in the desired direction.

In the modification shown in longitudinal 80 sectional elevation in Figure 2, a shoulder is formed at a³ by a thickening of the firing tube A, which shoulder abuts against the front face b² of the jacket B. In this example the turned down portion is dispensed 85 with in the back part of the tube, thus allowing a tube of less thickness to be employed.

Naturally, the stop a³, instead of being formed at the end of a thickened portion of a tube continuing down to the mouth, may be formed by a simple collar on a tube which has not been thickened in a gradually increasing manner.

95 Figure 3 shows in sectional elevation a modification in which the jacket B and the removable firing tube A mounted with the clearance D, are assembled together by means of a sleeve E having an internal thread and adapted to screw on to a screw-thread end B¹ of the jacket. In this example the front face of the jacket abuts against a collar A¹ on the firing tube, which collar in its turn abuts against a shoulder e 100

on the sleeve E. In order to prevent any rotation of the tube A relatively to the jacket B, it is convenient to provide the front face of the jacket with a certain number of notches or teeth engaging in spaces between the corresponding notches on the collar A¹.

Having now particularly described and ascertained the nature of my said invention and in what manner the same is to be performed, I declare that what I claim is:—

1. A gun comprising a rifled firing tube and a jacket, the rear end of said tube extending into said jacket and having the outer diameter of the rear portion thereof less than the inner diameter of the jacket, and screw-threaded means for removably securing said firing tube to said jacket, the threads of said means being formed in a direction opposite to the rifling of the tube

20 and being provided adjacent the front end of the jacket whereby said firing tube is readily removable from the jacket which assists in withstanding the transverse stresses set up in the rear portion of said tube during firing of the gun.

2. A gun comprising a rifled firing tube and a jacket provided with screw threads adjacent the forward end thereof, the rear end of said tube extending into said jacket 30 and being provided with means to engage said threads, the latter being formed in a direction opposite to the rifling of the tube, the outer diameter of the rear portion of the tube being less than the inner diameter of the jacket which is adapted to confine the rear end of the tube within its elastic limits under stress of fire while leaving play between the tube and jacket when relieved of such stress, whereby said tube is readily removable from said jacket.

3. A gun comprising a rifled firing tube and a jacket having a threaded portion, the rear end of said tube extending into the jacket and having an outer diameter normally less than the inner diameter of the jacket, and threaded means for the tube adapted to engage the threads of the jacket for maintaining said jacket and tube in cooperative relation, said threads being formed in a direction opposite to the rifling of the tube.

4. A gun comprising a rifled firing tube and a jacket having threads adjacent the forward end thereof, the rear end of said tube extending into the jacket and provided with threads formed in an opposite direction to the rifling of the tube for coaction with the threads of the jacket, the outer diameter of the rear portion of the tube being less than the inner diameter of the jacket and having a tensile strength such that the jacket assists in withstanding the transverse stresses set up in the tube at the instant of firing, said tube being provided with a shoulder adapted to abut against a

portion of the jacket, the reaction resulting from the rotation of a projectile passing through the tube serving to force said shoulder more tightly into engagement with the jacket.

5. A gun of the type comprising inner and outer portions, the inner diameter of the outer portion and the outer diameter of the inner portion being such that the outer portion confines the inner portion within its elastic limit under firing stresses while leaving play between said inner and outer portions when relieved of said stresses, said inner and outer portions being provided with coacting threads and the inner portion being rifled, the rifling and threads being so formed that the reaction resulting from the passage of a projectile through the inner portion tends to move the latter inwardly relative to the outer portion.

6. A gun comprising an inner rifled portion and an outer portion, a shoulder on one of said portions having abutting engagement with the other portion, threaded means for securing said portions in cooperative relation, the threads of said means being cut in a direction opposite to the rifling whereby the reaction resulting from the rotation of a projectile passing through the inner portion acts through said threads and forces said shoulder more closely into engagement with the abutting portion.

7. A gun comprising, in combination, a jacket and a rifled firing tube having the rear portion thereof extending within the bore of the jacket, said tube being provided with means adapted to engage threads formed in the forward portion of said jacket, said threads being formed in a direction opposite to the rifling of said firing tube, the outer diameter of the rear portion of the part of the tube extending rearwardly from the plane of the threads of the jacket being less than the inner diameter of the jacket, and said diameters being so proportioned that the jacket confines said tube within its elastic limits under the stress of firing while leaving play between the tube and jacket when relieved of such stress, whereby said tube is rendered easily removable.

8. A gun of the type described comprising, in combination, a jacket and a rifled firing tube extending into said jacket, said tube being provided with a shoulder adapted to engage the end of said jacket, and the latter being provided with a sleeve surrounding said tube and adapted to engage said shoulder and the threads of said jacket for preventing longitudinal displacement of the tube and jacket.

9. A gun comprising, in combination, a jacket, a rifled firing tube extending into said jacket and provided with a shoulder adapted to engage the jacket, screw threads formed in the jacket adjacent the forward

end thereof for coacting with said tube to maintain the latter in operative relation with the jacket, said screw threads being formed in a direction opposite to the rifling of the tube, and the inner portion of said tube being confined within said jacket within its elastic limits under the stress of fir-

ing and being so constructed that play is left between the tube and jacket when the former is relieved of said stress, whereby 10 said tube is rendered easily removable.

In testimony whereof I have signed this specification.

NICOLAS EMILIEN METHLIN.
